W. S. WELLS,
SHUTTLE TENSION,
APPLICATION FILED DEC. 9, 1919.

1,354,362.

Patented Sept. 28, 1920.

WITNESS

Wm. S. Wells

INVENTOR,
William S. Wells,
BY *John Stewart*,
ATTORNEY.

UNITED STATES PATENT OFFICE.

WILLIAM S. WELLS, OF SOUTH BETHLEHEM, PENNSYLVANIA.

SHUTTLE TENSION.

1,354,362.

Specification of Letters Patent. Patented Sept. 28, 1920.

Application filed December 9, 1919. Serial No. 343,593.

To all whom it may concern:

Be it known that I, WILLIAM S. WELLS, a citizen of the United States, residing at South Bethlehem, in the county of Lehigh and State of Pennsylvania, have invented certain new and useful Improvements in Shuttle Tensions, of which the following is a specification.

This invention relates to tension means for shuttles having rotary weft packages and means to guide the weft in tangential relation to the package in being withdrawn therefrom, and more particularly it relates to tension means of this class in which a braking device bears against the package and the braking pressure of said device is controlled by the weft. The principal object of the invention is to provide a tension device of the class indicated which may be made to preserve a more equable tension than the known devices, regardless of whether the pull on the weft comes suddenly or gradually.

In the drawing,

25 Figure 1 is a plan view of a shuttle embodying the present invention,

Fig. 2 is a sectional view on line 2—2 of Fig. 1;

30 Figs. 3 and 4 are details illustrating different positions of the parts; and

Fig. 5 is a detail illustrating how the device is adjusted.

In the shuttle body (which may be of any form, that shown being intended for use in 35 the loom set forth in my Letters Patent No. 1,319,196), which includes the body proper or shell *a* and the bow *b*, is arranged the thread package, here taken as consisting of a core *c* journaled in the shell in the bearings *d* and the weft windings *e* on the core.

The bow has a pair of thread guides *f* opposite the transverse center of the package.

45 In one side of the bow is freely pivoted the brake member *g* in the form of a blade whose free end is adapted to bear against the package, as shown.

To the other side of the bow is fixed the pressure member *h*, here shown as a spring blade.

50 *i* designates a spiral spring having at one end a thread guide *j*. The end of the pressure member *h* has a hole *k* therein which is of less diameter than the spring *i* but of 55 suitably greater gage than the thickness of each coil of the spring. The spring is in

effect screwed into this hole, as shown best in Fig. 5, and since it is tight-wound (the coils thereof when it is relaxed abutting or approximately abutting each other) it is held firmly in place in member *h*. As mounted in said member *h* it stands at one side of the central transverse axis of the shuttle, its inner end abutting member *g*.

l is a stop projecting inwardly of the bow and adapted to limit the inward movement of the brake member *g* when the package is removed from the shuttle.

In use the thread from the package extends first through one guide *f*, then through the guide *j* and then through the other guide *f* (the threading of the guides being readily accomplished upon holding guide *j* between and in alinement with guides *f*). Each time the thread is subjected to a pull, it first more or less extends the relatively lighter spring before it can effect any reduction of the pressure of the spring member *h* on the brake member *g*. The action of the device is thus rendered extremely delicate, and however sudden or violent the pull may be the release of the package is always gradual, so that an equable or uniform tension is the result, it being understood that the device is first adjusted to suit the work it is called on to do by turning the spring *i* and thus screwing it in member *h*; the turning or screwing in one direction results in increased distance between members *g* and *h*—and reduces the free or thread-guide—including portion of the spring (which stiffens the action of the device) and in the other direction results in reducing the distance between said members and increasing the free end portion of the spring (which eases or relaxes the action of the device).

In view of Figs. 3 and 4 it will be seen that friction between the spring *i* and member *g* as a factor interfering with the free play of the parts is avoided because the spring maintains a constant position of contact with said member, bending one way or the other as the members *g* and *h* move to different angular positions with reference to each other.

Having thus fully described my invention, what I claim as new and desire to secure by Letters Patent is:—

1. In combination, the shuttle body having means to support a rotary thread package and also having a thread guide, and means, controlled by the thread, to exert

braking pressure on the package including a spring member attached to the body and a spiral spring thread guiding device screwed into said member.

5. In combination, the shuttle body having means to support a rotary thread package and also having a thread guide, a brake member for the package, and means, controlled by the thread, to exert pressure on the brake member including a pressure member attached to the body and a spiral spring screwed into one member and bearing against the other.

15. In combination, the shuttle body having means to support a rotary thread package and also having a thread guide, a brake member for the package, and means, controlled by the thread, to exert pressure on the brake member including a pressure member attached to the body and a spiral spring screwed into one member and bearing endwise thereof against the other.

25. In combination, the shuttle body having means to support a rotary thread package and also having a thread guide, a brake member for the package, and means, controlled by the thread, to exert pressure on the brake member including a pressure member attached to the body and a spiral spring screwed into one member and bearing endwise thereof against the other, said members being movable into different angular relations to each other.

35. In combination, the shuttle body having means to support a rotary thread package and also having a thread guide, a brake member for the package, and means, controlled by the thread, to exert pressure on the brake member including a pressure

member attached to the body and a spiral spring screwed into one member and bearing at one end against one member and having a thread guide at the other end thereof.

6. In combination, the shuttle body having means to support a rotary thread package and also having a thread guide, and means, controlled by the thread, to exert braking tension on the package including a plate spring member attached to the body and a spiral spring thread guiding device attached to and projecting from said member.

7. In combination, the shuttle body having means to support a rotary thread package and also having a thread guide, a brake member for the package, and means, controlled by the thread, to exert pressure on the brake member including a pressure member attached to the body and overlying the brake member and a spiral spring carried by the pressure member and bearing at one end against the brake member and having at its other end a thread guide.

8. In combination, the shuttle body having means to support a rotary thread package and also having a thread guide, and means, controlled by the thread, to exert braking pressure on the package including a blade-like brake member attached at one end to said body and bearing at the other end against the package and a spring means bearing against the brake member near the first-named end of the latter and including a blade spring attached at one end to said body.

75. In testimony whereof I affix my signature.

WILLIAM S. WELLS.
